UNITED STATES PATENT OFFICE.

FRANK W. BEBERDICK, OF WEST HOBOKEN, NEW JERSEY.

DESIGN FOR A PATTERN FOR BICYCLE-TROUSERS.

SPECIFICATION forming part of Design No. 30,222, dated February 14, 1899.

Application filed November 8, 1898. Serial No. 695,895. Term of patent 14 years.

To all whom it may concern:

Be it known that I, FRANK W. BEBERDICK, a citizen of the United States, residing at West Hoboken, in the county of Hudson and State 5 of New Jersey, have invented and produced a new and original Design for a Pattern for Bicycle-Trousers, of which the following is a specification, reference being had to the accompanying drawing, forming part thereof.

10 The drawing represents in plan view a pattern of one side and half of the back of the bicycle-trousers, showing my new design, and it will be understood that the other side and half of the back are the same.

15 As shown in the drawing, the leading or material feature of my design consists in the part A, forming one side and half of the front, and the part B, forming half of the back, and in the particular shape or contour 20 given to the upper edge or ends of these parts. From the point a the outer edge of the part A extends upwardly and outwardly in a curved line deviating only slightly from a straight line to the point a' , from which point 25 the edge extends upwardly and inwardly in a curved line to the point a'' and from thence upwardly in a substantially straight line, which is inclined inwardly to the point a^3 . From the point a^3 the edge of the part A ex- 30 tends inwardly and downwardly in a straight line to the point a^4 , from which point the edge extends downwardly in a substantially straight line to the point a^5 , and from thence the edge extends inwardly in a curved line to 35 the point a^6 . From the point a^6 the edge extends downwardly and outwardly in an outward and then inward curve to the point a^8 , forming the compound-curved line a^7 . From the point a^8 the edge of the part A extends 40 outwardly and slightly upwardly in a curved line to the point a . The edge between the points a and a^8 is somewhat shorter than the edge between the points a^3 and a^4 , but has substantially the same inclination. From

the point b the edge of the part B extends 45 upwardly in an outwardly and then inwardly curved line b' to the point b^2 . The line b' is inclined outwardly from the vertical. From the point b^2 the edge of the part B extends upwardly and is curved inwardly to the point 50 b^3 , from which point the edge extends upwardly in a substantially straight line to the point b^4 , which point is located in substantially the same vertical plane as the point b . From the point b^4 the edge of the part B ex- 55 tends inwardly in a line which is curved first upwardly and then downwardly to the point b^6 , forming the compound-curved line b^5 . The point b^6 is located in substantially the same horizontal plane as the point a^3 of the 60 part A, but below the horizontal plane of the point b^4 . From the point b^6 the edge of the part B extends downwardly in a curved line to the point b^7 , from whence the said edge extends downwardly in a full outward curve 65 to the point b^8 . From the point b^8 the edge of the part B extends in an upwardly-curved line to the point b , which point is located in substantially the same vertical plane as the point b^4 and slightly below the point b^8 . The 70 said point b is located in the same horizontal plane as the point a^8 . The points b^2 and a^6 are located in the same horizontal plane and are in contact with each other.

Having fully described my invention, I 75 claim as new and desire to secure by Letters Patent—

The design for pattern for bicycle-trousers as herein shown and described.

In testimony that I claim the foregoing as 80 my invention I have signed my name, in presence of the subscribing witnesses, this 5th day of November, 1898.

FRANK W. BEBERDICK.
